UNITED STATES PATENT OFFICE.

HORATIO G. GILLMOR, OF WASHINGTON, DISTRICT OF COLUMBIA.

RAIL-ANCHOR.

1,261,119.

Specification of Letters Patent.

Patented Apr. 2, 1918.

Application filed June 29, 1916. Serial No. 106,646.

To all whom it may concern:

Be it known that I, HORATIO G. GILLMOR, a citizen of the United States, residing at Washington, in the District of Columbia, 5 have invented a new and useful Improvement in Rail-Anchors, of which the following is a specification, accompanied by drawings.

This invention relates to devices known as 10 rail anchors, rail stays or anticreepers and one of its objects is to form a simple device which will prevent the longitudinal or creeping movement of the rails of railways.

Another object is to provide a device of 15 the character mentioned which will be effective in preventing the movement of the rails in either direction.

Another object is to provide a device 20 which may be used in connection with a tie plate and which when so used will not affect the relations of the rail and the tie plate but will leave the rail free to move slightly vertically in relation to the tie plate under the wave movement of the rail and at the same 25 time effectually hold the rail against creeping tendencies.

Another object of the invention is to provide a device which shall grip the rail above the surface of the ballast and which shall 30 therefore be free from interference with its efficient action by the ballast.

The preferred form of the invention is 35 illustrated in the accompanying drawings, in which:—

Fig. 1 is an end view, showing the rail, tie plate and shoe in section.

Fig. 2 is a side elevation, showing the device in place with the tie plate in section.

Fig. 3 is a plan view of the device in 40 operative position upon the rail.

Fig. 4 is an end view, showing some of the parts in section, illustrating the manner in which the device is applied to the rail.

Similar letters apply to similar parts 45 throughout the several views.

In the embodiment of the invention illustrated in the drawing, the rail is represented by A. The rail A is of the usual construction and has a head B and a base flange C 50 and is supported upon a tie plate D, which in turn is supported upon the tie E to which it is secured by the spikes or screws F. The tie plate D may be provided with a rib G arranged to engage one edge of the rail 55 base C and has at the other side of the rail base C an aperture H generally similar to

the apertures traversed by the spikes or screws F.

The shoe I is constructed to engage the upper surface and the edge of the rail base 60 C at one side of the rail and this shoe I may be constructed with a portion K, which projects below the rail base C and engages the aperture H in the tie plate D. The shoe I is formed with a groove L having ribs M 65 at each side connected to stiffening ribs N and may be formed with a portion O which forms an aperture Q for a purpose to be later described. The groove L is preferably formed with a curved surface R for a portion 70 of the bottom of the groove, and the portion K of the shoe I has portions S projecting laterally.

The bar U has a portion V which extends downwardly below the edge and bottom of the rail base C and into the aperture H in the tie plate D, traversing this aperture and the aperture Q in the shoe I. It has such form as to provide a curved surface W for engagement with the curved 80 surface R at the bottom of the groove L of the shoe I and is arranged to be received in the groove L of the shoe I.

The device is applied to the rail, after the tie plate has been placed and secured in 85 the customary manner, by placing the shoe in position on the rail with the portion K engaging the aperture H in the tie plate D. In this position the portions S of the portion K of the shoe I will engage the two opposite sides of the aperture H in the tie plate D but the portion K of the shoe I will be free to slight lateral movements in the aperture H. The bar U is placed with the portion V traversing the aperture Q in the 95 shoe I and its end entered in the aperture H of the tie plate D as illustrated in Fig. 4. When forced down until the head engaging portion Y of the bar U will just begin to engage the under side of the head 100 B of the rail A the curved surface W of the bar U will just begin to engage the curved surface R of the bottom of the groove L in the shoe I. The bar U may then be forced to the final operative position illustrated in 105 Figs. 1, 2 and 3 by driving the upper portion of the bar U transverse to the rail until the head engaging portion Y of the bar U is in full engagement with the under surface of the rail head B. In doing this the bar 110 U is deformed, its shape being changed from that shown in Fig. 4 to that shown in

Fig. 1. The bar U during this process of forcing it into position will first fulcrum upon the curved surface R of the bottom of the groove L in the shoe I and the portion 5 V will engage the outer side of the aperture H in the tie plate D and exert transverse pressure upon the tie plate D pressing the rib G and the spikes or screws F against the opposite edge of the base C. As the bar U 10 moves to position it is deformed and the surface W engaging the surface R of the bottom of the groove L in the shoe is increased until in the final position of the parts the bar U engages the whole or nearly 15 the whole of the bottom of the groove L in the shoe I. In this final operative position of the parts there is exerted by the bar U a pressure transverse to the rail pressing the rib G and the spikes F against the edge 20 of the rail base C, a pressure, transverse to the rail in the opposite direction, upon the shoe I pressing this shoe I upon the opposite edge of the rail base C, a downward pressure upon the shoe I which presses the 25 shoe I downward upon the top surface of the rail base C, and a vertical pressure of the portion Y upon the under side of the rail head B. The rail is in this way effectually gripped by the device so as to hold it 30 in position longitudinally upon the tie plate D and the tie E, but the rail is left free to the slight vertical movements of the rail in relation to the tie plate which wave motion of the rail may tend to produce. Moreover 35 the bar U, in tending to resume its normal unstressed form is pressed up against the under side of the head B of the rail and this engagement of the portion Y of the bar U with the head B of the rail locks the parts 40 in position, the bar U being held in position laterally by the engagement of the portion V with the tie plate D and the shoe I and being held in vertical position by the engagement of the portion Y which is pressed 45 upwardly against the under side of the head B of the rail.

Should the rail tend to move in the direction of the arrow in Fig. 2 and the initial grip of the parts upon the rail be not sufficient to resist the stresses tending to produce this movement the rail will move slightly in the direction of the arrow. This movement will carry the upper portion Y of the bar U which is pressing up against the 50 under side of the head B of the rail with the rail and the bar U will cant slightly and assume the position shown by the dotted lines in Fig. 2 and will in this way increase the pressure of the bar U downward upon the shoe I and the shoe I downward upon 55 the upper surface of the rail base C and in this way the grip of the device upon the rail will be automatically increased and the further movement of the rail in the direction 60 of the arrow prevented.

It will be understood that, should the tendency of the rail to creep, be in a direction the reverse of that indicated by the arrow, the action of the device will be the same but that the bar U will, if such creeping movement takes place, move slightly and cant in the direction opposite to that indicated by the arrows in Fig. 2 and the movement of the rail will be self checked by the action of the device. The anchor is thus effective 75 in preventing creeping movement of the rail in either direction. 70

By suitably forming the shoe I and the bar U they may be arranged to engage any spike aperture H in the tie plate D so that 80 they may be used with any tie plate already in use either by omitting one of the spikes or screws F or by drawing one which has been applied and substituting the shoe I and the bar U. 85

The bar U may be made in spring steel and, when made of this material and suitably tempered, the pressures exerted by the bar U upon the shoe I and the rail head B may be made as great as desired by suitably 90 proportioning the bar. The bar U need not necessarily be made of this material and the invention is not limited to the particular configuration illustrated, as it may be embodied in various other forms. 95

What I claim and desire to secure by Letters Patent is—

1. A device for preventing the creeping of rails, comprising rail gripping elements, one of which is a part engaging the rail base at one side of the rail, and one of which is a vertically disposed member engaging said part and the rail head and having its lower end held in fixed position in the roadbed. 100

2. A rail anchor comprising rail gripping elements, one of which is provided with means for engaging the bottom and one side of the rail base and with means for giving the device a fixed position in the road bed 105 as against the tendency of the rail to creep, one of which is a shoe engaging the other side of the rail base, and one of which engages the under side of the rail head and the other elements and exerts pressure thereon. 110

3. A rail anchor comprising a holding plate having means for engaging one side of the base of the rail, a bar engaging said holding plate and the under side of the head of the rail at the other side of the rail 115 and a part which intervenes between said bar and the upper surface of the rail base. 120

4. As a new article of manufacture, an anticreeping device for attachment to a tie plate comprising a shoe constructed to engage the rail base and a bar constructed to engage the tie plate and to be forced in between said shoe and the under side of the head of the rail. 125

5. As a new article of manufacture, a rail 130

5 anchor for attachment to a tie plate comprising a rail base engaging part and a spring constructed to engage the tie plate and to be forced in between said part and the under side of the rail head at one side of the rail.

10 6. A rail stay comprising a part having an abutment which engages the rail base at one side of the rail and means for giving said part a fixed position in the road bed as against the tendency of the rail to creep, a shoe which engages the upper surface of the rail base at the other side of the rail and a bar engaging said part and said shoe 15 and the rail head.

20 7. A rail anchor comprising an element having means for engaging the rail base across the bottom and at one side of the rail and with means for engaging other parts at the other side of the rail, a shoe engaging the edge of the rail base and the elements at the side of the rail opposite to that engaging said element, a bar engaging the element and said shoe and the under side 25 of the rail head, one of said elements being provided with means for giving the device a fixed position in the road-bed.

30 8. A device for preventing the creeping of rails comprising a tie plate provided with means for engaging the rail base at one side of the rail, a part which engages the rail base at the other side of the rail and a spring engaging the tie plate and forced in between the under side of the rail head and 35 said part.

40 9. An anticreeper comprising a tie plate, a part engaging said tie plate and the under side of the head of the rail at one side of the rail and an element which intervenes 45 between said part and the rail base.

10. A rail anchor comprising a tie plate, a spring engaging said tie plate and the rail head at one side of the rail and an element which intervenes between the spring 45 and the rail base.

11. A device for preventing the creeping of rails comprising a holding plate, a shoe engaging the rail base and a bar engaging said holding plate and shoe and the under side of the head of the rail at one side of 50 the rail.

12. A rail anchor comprising a holding plate, a shoe engaging said holding plate and the rail base at one side of the rail and a bar engaging said shoe and holding plate and the under side of the head of the rail for effecting the gripping action of the 55 parts.

13. An anticreeper device comprising a tie plate, an element engaging the upper surface of the rail base at one side of the rail and a part engaging the tie plate and arranged to be forced in between the under side of the rail head and said element.

60 14. A rail anchor comprising an element

provided with means for engaging the rail base at one side of the rail and with an aperture at the other side of the rail and with means for giving said element a fixed position in the roadbed as against the tendency of the rail to creep, a shoe engaging the rail base and a deformable bar engaging the aperture in said element and forced in between said shoe and the under side of the head of the rail.

70

75

15. A rail stay comprising a holding plate, a rail base engaging element and a bar engaging said holding plate said element and the under side of the rail head and exerting pressure thereon in tending 80 to resume a position from which it was sprung.

20 16. A device for preventing the creeping of rails comprising a tie plate, a shoe engaging the rail base and a bar engaging the tie plate and shoe and the under side of the head of the rail at one side of the rail and exerting pressure thereon in tending 85 to resume a position from which it was sprung.

90

25 17. A device for preventing rail creeping comprising a tie plate, a shoe engaging the rail base and a spring engaging the tie plate and shoe and the under side of the head of the rail at one side of the rail and 95 exerting pressure upon said tieplate shoe and rail in tending to resume a position from which it was sprung.

30 18. An anticreeper device including, in combination with the rail and a tie plate, a 100 part engaging the rail base and a bar so engaging said tie plate and said part and the rail head that longitudinal movement of the rail in relation to the tie plate will cant said bar and automatically increase the grip 105 of the device upon the rail.

110

35 19. A device for preventing the creeping of rails including, in combination with the rail and a tie plate a shoe engaging the rail base at one side of the rail and a spring so 115 engaging the tie plate and said shoe and the under side of the rail head that creeping movement of the rail in relation to the tie plate will produce angular movement of said spring and automatically increase the hold of the device upon the rail.

40 20. A rail anchor comprising a tie plate a shoe and a part constructed to engage said tie plate and shoe and to be forced into engagement with the under side of the rail 120 head by transverse angular movement in relation to the rail.

115

45 21. An anticreeper comprising a holding plate, a part constructed to engage the rail base and a bar so engaging said holding 125 plate and part that it may be forced in between the rail head and said part while engaging said holding plate by angular movement in relation to the rail and that when in position longitudinal movement of 130

- the rail in relation to the holding plate will produce angular movement of said bar which will increase the pressure of the device upon the rail.
- 5 22. A rail anchor, comprising a part adapted to engage the rail base at one side of the rail, a vertically disposed member constructed to engage said part and to be driven in between said part and the rail head, and means 10 operating upon the lower end of said vertically disposed member for giving it a fixed position in the roadbed.
- 15 23. A device for preventing the creeping of rails, comprising a shoe engaging the rail base, a bar engaging said shoe and the rail head, said bar being held in position by the spring action of said bar in tending to assume a position from which it was sprung, and tie engaging means acting upon one end 20 of said bar.
- 25 24. An anticreeping device for rails, comprising a shoe engaging one side of the rail foot flange, a bar engaging said shoe and the rail head, said bar being held in engaging position by the spring action of said bar in tending to assume a position from which it was sprung, and a tie plate engaging the edge of the rail base opposite said shoe and coöperating with the other elements to give 30 the lower end of said bar a fixed position in the roadbed.
- 35 25. An anticreeper, comprising rail gripping elements engaging the rail base at opposite sides of the rail, a vertically disposed part engaging one of said elements and the rail head, and means operating upon the lower end of said vertically disposed part for giving it a fixed position in the roadbed.
- 40 26. A device for preventing the creeping of rails, comprising two members engaging opposite sides of the rail, and a resilient bar engaging one of said members and the rail head, said members and said bar coöperating 45 to give the lower end of said bar a fixed position in the roadbed and to press said members against the rail.
- 50 27. An anticreeper, comprising a holding plate and a shoe engaging opposite sides of the rail, and a resilient vertically disposed bar engaging with said shoe, and the under side of the rail head for locking the parts in operative position on the rail.
- 55 28. A rail anchor, comprising a part transversely disposed beneath the rail and provided with means for engaging one edge of the rail base, a shoe engaging the rail base at the other side of the rail, a vertically disposed bar, and means for preventing the 60 lower end of said bar from moving with the rail, said part, shoe and bar so engaging that said bar may be driven into engagement with said shoe and the head of the rail and a transverse pull be thereby exerted upon 65 said transverse part.
29. A rail anchor, comprising a shoe engaging the rail base at one side of the rail, a vertically extending part engaging the rail head and said shoe, and a transversely extending part provided with means for 70 engaging the rail base at the side of the rail opposite to said shoe, said transversely extending part and said shoe coöperating to hold the lower end of said vertically extending part in fixed position in the roadbed 75 while permitting vertical movement of the rail in relation to said transversely extending part.
30. An anticreeper, comprising a tie plate and a shoe engaging the rail base at opposite 80 sides of the rail, and a vertically disposed part engaging the shoe and the rail head, said tie plate and shoe coöperating to give the lower end of said part a fixed position in the roadbed while permitting vertical 85 movement of the rail in relation to said tie plate.
31. A rail stay, comprising a holding plate provided with means for engaging the edge of the rail base at one side of the rail, a rail base engaging part at the other side of the rail, and a rail head engaging part, said elements coöperating to press said holding plate and said base engaging part against the rail and to give the lower end of said 90 rail head engaging part a fixed position in the roadbed.
32. A rail stay, comprising a rail head engaging part, a tie plate provided with means for engaging the edge of the base at one side 100 of the rail, and a shoe engaging the rail base at the other side of the rail, said elements coöperating to press said shoe against the rail to subject the tie plate to a transverse stress, pressing said edge engaging means 105 against the rail base.
33. An anticreeper for rails, comprising a shoe engaging one side of the rail base, a vertically extending member engaging the head of the rail and said shoe, a transversely 110 extending part provided with means at one end for engaging the rail base opposite said shoe and with means at the other end thereof coöperating with the other elements to subject said vertically extending part to a 115 bending strain, and tie engaging means operating upon one end of said vertically extending part.
34. An anticreeper for rails, comprising a shoe engaging one side of the rail base, a vertically extending member engaging the head of the rail and said shoe, a plate provided with means for engaging the rail base opposite said shoe and with means for so 120 engaging one of the other elements as to subject said vertically extending part to a bending strain, and means for giving one of said elements a fixed position in the roadbed 125 in opposition to the tendency of the rail to creep.

35. A rail anchor, comprising a rail base engaging shoe, a rail head and shoe engaging member, means for engaging said rail head and shoe engaging member for subjecting said member to a bending strain, and means for securing one end of said member against longitudinal movement.

36. An anticreeper, comprising a rail base engaging element, a shoe engaging the rail base at one side of the rail, a resilient member engaging said shoe and the rail head, and means engaging with a cross tie and preventing forward movement of said member, said member being pressed upward against the rail head by the spring action of said member.

37. An anticreeper, including an element adapted to engage the rail head and a rail base engaging shoe at one side of the rail and exerting pressure thereon in tending to assume a position from which said element has been sprung.

38. An anticreeping device, including a rail engaging member adapted to grip the upper surface of the rail base flange and a spring engaging said member and arranged to be driven transversely of the rail and wedged between the head of the rail and said rail engaging member.

39. An anticreeping device for rails, comprising rail gripping elements, one of which is provided with means for engaging the bottom and one side of the rail base and with means for giving the device a fixed position in the roadbed as against the tendency of the rail to creep, one of which is a shoe engaging the other side of the rail base, and one of which engages the underside of the rail head and said shoe and exerts pressure thereon.

40. As a new article of manufacture, an anticreeping device for attachment to a tie plate, comprising a shoe constructed to engage the rail base and the tie plate at one side of the rail and a part constructed to engage said shoe and to be forced in between said shoe and the under side of the rail head.

41. As a new article of manufacture, an anticreeping device for attachment to a tie plate, comprising a rail base engaging part and a spring constructed to engage said part and to be forced in between said part and the under side of the rail head.

42. A rail stay, comprising a part having an abutment which engages the rail base at one side of the rail and means for giving said part a fixed position in the roadbed as against the tendency of the rail to creep, a shoe which engages the upper surface of the rail base and said part at the other side of the rail, and a bar engaging said shoe and the rail head.

43. A rail anchor, comprising a holding plate, and a shoe engaging said holding

plate and the rail base at one side of the rail, and a bar engaging said shoe and the under side of the head of the rail for effecting a gripping action.

44. An anticreeping device, comprising a tie plate and an element engaging the upper surface of the rail base and said tie plate at one side of the rail, and a part arranged to be forced in between the under side of the rail head and said element.

45. A device for preventing the creeping of rails, comprising a tie plate, a shoe engaging the rail base and tie plate at one side of the rail, and a spring engaging the shoe and the underside of the head of the rail and exerting pressure thereon.

46. A device for preventing the creeping of rails, comprising a holding plate, a part engaging the rail base and said holding plate, and a bar so engaging said part and the rail head that longitudinal movement of the rail in relation to the holding plate will cant said bar and automatically increase the grip of the device upon the rail.

47. A rail anchor, comprising a holding plate, engaging the rail base at one side of the rail, and a fixed portion of the roadbed in opposition to the tendency of the rail to creep, a shoe engaging the rail base and the holding plate at the other side of the rail, and a spring so engaging the shoe and the under side of the head of the rail that creeping movement of the rail will produce angular movement of said spring and automatically increase the hold of the device upon the rail.

48. A rail anchor, provided with means for giving it a stationary position with respect to the roadbed and with rail clamping means, comprising a transverse element engaging the rail base at one side of the rail, a shoe engaging said transverse element and the rail base at the other side of the rail, and a resilient bar engaging said shoe and the under side of the rail head.

49. A rail anchor, provided with means for giving it a fixed position with respect to the roadbed and with rail clamping means, comprising a shoe engaging the rail base at one side of the rail, and a spring which is forced in between the head of the rail and said shoe.

50. An anticreeper, provided with means for giving it a stationary position with respect to the roadbed and with rail clamping means, comprising co-engaging members, one of which is a shoe, engaging the rail base at one side of the rail, and one of which is a spring engaging said shoe and the under side of the rail head and exerting pressure thereon.

51. A device for preventing the creeping of rails, provided with means for giving it a stationary position in the roadbed, comprising co-engaging members, one of which

is a part engaging the rail base at one side of the rail and one of which is resilient and provided with rail head and shoe engaging portions, said members interlocking and exerting transverse and vertical gripping pressure upon the rail.

52. A device for preventing the creeping of rails, including elements adapted to grip

the rail, a spring engaging one of said elements and arranged to be driven transversely 15 of the rail and wedged in between said element and the rail head, and means whereby one of said elements is held in fixed position in the roadbed.

H. G. GILLMOR.
